UNITED STATES PATENT OFFICE.

FRANCIS L. BARSTOW, OF APPLETON, WISCONSIN.

PAPER-STOCK SOAK-TANK.

1,150,163.

Specification of Letters Patent. Patented Aug. 17, 1915.

Application filed October 19, 1914. Serial No. 867,320.

To all whom it may concern:

Be it known that I, FRANCIS L. BARSTOW, a citizen of the United States, and resident of Appleton, in the county of Outagamie and State of Wisconsin, have invented certain new and useful Improvements in Paper-Stock Soak-Tanks; and I do hereby declare that the following is a full, clear, and exact description thereof.

10 My invention consists in what is herein particularly set forth with reference to the accompanying drawings and pointed out in the claims of this specification, its main object being to facilitate the unloading of 15 paper-stock, after treatment of the same in a soak-tank, and to make the work less disagreeable to operatives than is usually the case. Loading of the tank is also facilitated.

20 Figure 1 of the drawings represents a partly sectional elevation of a paper-stock treating apparatus comprising my improvements; together with an adjacent track structure and a truck thereon, the plane of 25 the section being indicated by line 1—1 in Fig. 2, which Fig. 2 represents a partly sectional plan view indicated by line 2—2 in Fig. 1, parts of the apparatus being removed. Fig. 3 represents a fragment of the 30 apparatus aforesaid partly in section on the plane indicated by line 3—3 in Fig. 2; Fig. 4, a cross-section of a detail of said apparatus on the plane indicated by line 4—4 in Fig. 1; Fig. 5, a plan view of a detail of the 35 same apparatus partly in horizontal section on the plane indicated by line 5—5 in Fig. 1; Fig. 6, a sectional view of another detail of the apparatus, the section being indicated by line 6—6 in Fig. 7, which Fig. 7, 40 is a view indicated by line 7—7 in Fig. 6.

Referring by numerals to the drawings, 8 indicates a cylindrical soak-tank set to extend above and below a floor-line 9, the bottom of the tank being provided with a depending central stuffing-box 10 in which a hydraulic plunger 11 is guided, the plunger being operated from a cylinder (not shown) below said tank.

45 Bolted in connection with an upper outer flange of the plunger is the spider 12 of the apparatus, and fast on said spider over the arms of the same, are I-beams 13 upon which to support vertical division plates 14 having sides thereof provided with upper 50 and lower right-angle stiffening-bars 15, 16. Laid in on the lower stiffening-bars 16 of

the division plates are perforated sector plates 17, and these sector-plates in the arrangement specified are sections of what constitute the false-bottom of the tank.

Supported in connection with the spider is the upwardly extending central circulating-pipe 18 of the apparatus. This pipe has a foot 19 provided with a bottom opening through which the discharge-end of a 60 steam-supply pipe 20 extends when said spider and parts therewith are run down in the tank, and said opening is of sufficient area to admit the digesting liquor with which paper-stock in said tank is treated.

Attached to the upper end of the circulating pipe are the usual brackets 21 to which a conical deflecting hood is fastened, and in connection with the hood are brackets 22 supporting a horizontal plate 23 having a keyhole-slot therein, as is best shown in Fig. 5, this slot being for registration with a collar and bit stop 24 fast on a rod 25' depending from a lever 25 in connection with the operating-valve mechanism of the 70 apparatus.

The division plates 14 are riveted in slotted stay-arms 26' of collars 26 that are slipped on the circulating-pipe 18, and a stay ring 27 is similarly secured to the upper stiffening-bars 15 of said plates.

One of a series of guide-strips 28 is shown in the tank for engagement with a recess 29 in the spider to prevent said spider and parts therewith from turning when run down. The guide-strips are shorter than those usually employed, so that the spider may be elevated above the same for rotation, and, unless said spider is in correct position for lowering, the slot in the plate 23 85 will be out of register with the stop 24 on the rod 25', to prevent operation of the aforesaid valve-mechanism.

Bolted to the tank, outside of the same and at suitable intervals of its circumference, are flanges 30' of counter-bored bosses 30 having bayonet-slots 30'', and the boss-bores are in register with circular openings provided in said tank. Guided in each boss is a shouldered carrier 31 for a bolt 32 that 100 serves as a bearing for an anti-friction roller 33, and a spiral spring 34 is arranged in said boss to expand against the shoulder of the carrier. Diametrically opposite arms 31' of each carrier are shown engaging corresponding bayonet-slots in the guide for said carrier, but one of the arms and the slot for

same may be omitted. Stop-washers 35 are bolted to the outer end of each boss 30 in the path of the carrier with said boss, and the normal position of said carrier is such that the anti-friction roller on the bolt therewith is retracted clear of the spider in the tank. The spider being in its elevated position shown in Fig. 1, the carriers 31 are moved inward against spring-resistance to position the anti-friction rollers 33 under said spider, and the arms of said carriers are adjusted in bayonet-slots of the bosses 30 to prevent retraction of the carriers. The anti-friction rollers in the position last described prevent tilting of the spider when some of the load thereon is removed.

The spider being elevated as herein shown and described, portions of the cake of paper-stock may be removed with the perforated 20 sector-plates 17, onto the platform of a truck or other conveyance, said spider being intermittently rotated to bring the several sections of said cake to position for removal. As shown in Fig. 1, each of the sector-plates 25 may be provided with a stud 34 for connection with means for withdrawal of said plate and a section of cake thereon.

For de-inking old papers, the advantages of a soak-tank are well known to paper 30 makers, but heretofore the expense of handling the stock in loading and unloading operations has been difficult and expensive, because of not dividing the cake-elevator of such a tank into compartments having removable bottoms. Heretofore the expense of handling the stock has been considerable because of the necessity of breaking up the cake of de-inked paper-stock by digging said cake apart and pitching the particles thereof 35 into boxes on conveyer-trucks, something I avoid by providing for making the cake in sections that may be readily pulled out onto said trucks, as above explained, and the several compartments of said elevator may be 40 loaded, one at a time, more economically than by scattering and piling said material on the ordinary elevator.

I claim:

1. A paper-stock soak-tank having the 50 vertically movable false bottom thereof in removable sections, and upwardly extending division plates intermediate of said false bottom sections.

2. A paper-stock soak-tank having the 55 cake-elevator thereof provided with upwardly extending division plates, angle stiffening-bars attached to sides of the plates, and removable sections of the false-bottom of the tank laid in on stiffening-bars of said 60 plates.

3. A paper-stock soak-tank having I-beams

mounted on arms of the elevator-spider thereof, division plates supported on said beams, and removable sections of the false-bottom of the tank arranged between the 65 division plates.

4. A paper-stock soak-tank having the cake-elevator thereof provided with upwardly extending division plates between which to arrange removable sections of the 70 false-bottom of the tank, a circulating-pipe with said elevator, and collars on the pipe having stay-arms attached to said plates.

5. A paper-stock soak-tank having the cake-elevator thereof provided with upwardly extending division plates, upper and lower stiffening bars attached to sides of the plates, a stay-ring attached to the uppermost of the stiffening bars, the circulating pipe with said elevator, and collars on the pipe 80 having stay-arms attached to said plates, said lower stiffening bars being for the support of removable sections of the false-bottom of said tank.

6. A paper-stock soak-tank having the 85 cake-elevator thereof provided with upwardly extending division plates between which to arrange removable sections of the false-bottom of the tank, a hooded circulating pipe with the elevator, a guide in the 90 tank for registration with a recess in the spider of said elevator, a horizontal plate supported over the hood of said pipe and provided with a keyhole slot, and a valve-control rod having a collar and bit stop 95 thereon registrable with said slot when said guide and recess are in register.

7. A paper-stock soak-tank having the cake-elevator thereof rotatable when run up and divided into compartments of which 100 the bottoms are removable, and retractive anti-tilt stops for said elevator in its position aforesaid.

8. A paper-stock soak-tank having the 105 cake-elevator thereof rotatable when run up and divided into compartments of which the bottoms are removable, hollow outer bosses on the tank, a spring-controlled carrier in each boss having an arm engaging a bayonet slot with which the boss is provided, a support with the carrier, and an anti-friction roller on the support to be shot into said tank under said elevator in the position aforesaid.

In testimony that I claim the foregoing I 115 have hereunto set my hand at Appleton in the county of Outagamie and State of Wisconsin in the presence of two witnesses.

FRANCIS L. BARSTOW.
